UNITED STATES PATENT OFFICE.

HENRY FRIEDMAN, OF BROOKLYN, NEW YORK.

SLIPPER.

Application filed April 1, 1927. Serial No. 180,228.

This invention relates to footwear and particularly to an improved shoe known as a slipper, and has for an object to provide an improved arrangement whereby the stitching used in the sole is protected against ordinary wear.

A further object of the invention is to provide an improved slipper wherein an ornamental protecting edge is provided at the juncture of the sole and upper for presenting a convenient edging and at the same time presenting a protecting covering for the stitching.

In the accompanying drawing—

Figure 1 is a perspective view of a slipper, disclosing an embodiment of the invention.

Figure 2 is a bottom plan view of the slipper shown in Figure 1.

Figure 3 is an enlarged fragmentary sectional view through Figure 1 on line 3—3.

Referring to the accompanying drawing by numerals, 1 indicates the upper of a slipper and 2 the sole. The slipper as illustrated, is what is known on the market as a wool slipper, and heretofore was manufactured without the protecting and trimming edge 3. In the manufacture as heretofore, the sole 2 was stitched to the upper 1 by stitching 4, which is an over-and-over stitching of a well known kind. This over-and-over stitching 4 protected the lower edge of the upper and the sole and at the same time connected the parts together. During the use of the slipper, the lower part of the stitching 4 would wear and then the slipper would fall to pieces. To improve the appearance of the slipper and to protect the stitching 4, as well as the edge of the upper and the sole, the covering strip 3 has

been provided. This strip may be made of leather, cloth or other material and is held in place preferably by a line of stitching 5 extending directly through the two edge portions of the strip and through the edge portions of the upper 1 and the sole 2 as 40 illustrated in Figure 3. The protecting and covering strip 6 is stitched in place by a suitable line of stitching 7, said strip 6 being preferably of the same color and general appearance as the protecting or wearing 45 strip 3.

As illustrated in Figure 3, the lower part of strip 3 will receive the wear instead of the stitching 4 and, consequently, the stitching 4 is protected fully until the lower part 55 of strip 3 has been worn away. This construction lengthens the life of the slipper appreciably in addition to presenting a smooth edge to the sole.

What I claim is:

A slipper, comprising an upper having an outwardly extending margin, a sole formed of a size and shape to extend to the outer edge of said margin, a seam formed by an over-and-over stitch connecting the outer portion of the sole with said margin, said stitching and margin extending entirely around the sole, a protecting strip substantially U-shaped in cross section straddling said margin and the outer edge of said sole, 60 and a second line of stitching extending directly through both legs of said protecting strip, through said margin and the outer part of said sole for securing the protecting strip in place, and presenting additional securing means for connecting the margin of the upper and sole together.

HENRY FRIEDMAN.
